UNITED STATES PATENT OFFICE.

TRISTRAM S. LEWIS, OF KENDALLS MILLS, MAINE.

FOLDING BENCH.

Specification of Letters Patent No. 22,371, dated December 21, 1858.

To all whom it may concern:

Be it known that I, TRISTRAM S. LEWIS, of Kendalls Mills, in the county of Somerset and State of Maine, have invented a new and useful Improvement in Folding Benches; and I do hereby declare that the same is fully described and represented in the following specification and the accompanying drawings, of which—

10 Figure 1, is a top view; Fig. 2, is a bottom view; Fig. 3, a side elevation; Fig. 4, a longitudinal section and Fig. 5, a transverse section of a bench constructed with my invention and in an unfolded or opened state. 15 Fig. 6, exhibits a side view of it, as folded for convenience of transportation or of being packed in a small compass.

In such drawings A, and B, denote two boards having hinge blocks *a*, *b*, applied to 20 them, and so as to project below their abutting ends as shown in the drawing. These blocks have hinges, *c*, *d*, screwed to them for the purpose of connecting the two parts A, B, together and enabling one to be folded 25 down upon the other as shown in Fig. 6. Two sets of legs or supporters C, D, are also hinged respectively to the boards A, B, by hinges as shown at *e*, *f*, and so as to enable the legs either to be turned down flatwise, 30 against the underside of the board, as shown in Fig. 4, or turned out into right angles therewith as represented in the other figures.

For the purpose of maintaining the legs in the positions last stated, as well as to support the bench at its middle, and remove 35 from the hinges *c*, *d*, the strain of a weight laid on the bench, I employ in combination with the hinge blocks *a*, *b*, and the hinged legs C, D, a set of leg slides E, F, and a 40 confining wedge slide G. The leg slides

enter and slide through the hinge blocks and alongside of the wedge slide, and at their outer ends they abut against the cross bars *m*, *m*, of the legs as shown in the drawings each being connected with one 45 of the said bars by a draft band *o*, which is affixed to the slide and to the outer vertical edge of the said bar *m*, as shown in Fig. 4. The confining slide G, is not only placed within a groove *p*, made in the lower sides 50 of the boards A, B, but passes through the hinge blocks and is made wedge shaped or tapering, so that when forced through the two blocks, it shall fit tightly therein, and so press against the two leg slides E, F, 55 as to confine them in position and prevent them from being moved backward. It also crosses the joint between the two parts A, B, and by being driven into the two hinge blocks, receives the strain of a weight placed 60 on the top of the bench and thus prevents such from straining or breaking the hinges.

A bench made to fold and having appliances as above described, will often be found 65 very convenient, particularly as a wash bench or as a bench for a carpenter or other artisan.

I claim—

The combination and arrangement of the hinge blocks *a*, *b*, the leg slides E, F, and 70 the confining slide G, as applied to the parts A, B, and their legs C, D, connected or hinged together so as to fold up in manner substantially as specified.

In testimony whereof I have hereunto set 75 my signature.

TRISTRAM S. LEWIS.
